CLAIM

The ornamental design for a mock turtleneck, as shown and described.

DESCRIPTION

FIG. 1 is a front perspective view of a mock turtleneck showing my new design;

FIG. 2 is a rear perspective view thereof;

FIG. 3 is a front view thereof;

FIG. 4 is a rear view thereof;

FIG. 5 is a left side view thereof; and,

FIG. 6 is a right side view thereof.

The broken lines in the drawings depict boundaries of the claimed design and form no part of the claimed design.
